FLOAT

Edward R. Armstrong, Philadelphia, Pa.

Application December 7, 1944, Serial No. 567,067

8 Claims. (Cl. 114—43.5)

This invention relates to floats and anchorage systems therefor, and has as its main object to provide for float stabilization, regardless of wind and wave conditions or changes in deck loading. While the invention is not limited in its application, an important field of usefulness is in offshore drilling operations, and for this reason the embodiment to be hereinafter described by way of example takes the form of an offshore drilling rig.

In accordance with the invention the float comprises essentially a platform structure or deck supported on a suitable number of columnar buoyancy units. Such units are, in themselves, of great effect in equalizing energy effects released by wave action, and the reasons for this are fully set forth in my prior Patent No. 1,892,125, granted December 27, 1932. The anchoring means comprises a vertical system utilizing what I shall herein term "weight anchors," since they rely primarily on their weight for anchoring effect. During well drilling operations these anchors are bottomed and are so arranged as to effectively eliminate roll and pitch of the float due to water disturbances, and consequently the working platform is maintained entirely stable. Since the float should be mobile in order to be able to proceed to a new drilling location upon completion of a well, I provide means for the adjustment of buoyancy effects so that while the anchors are able to hold the float submerged below its normal flotation level during the building of a well, they are, nevertheless, liftable by the float to permit the free travel of the latter. This travel can be effected by the manipulation of horizontal mooring cables which are provided.

Without further general discussion, I shall describe the invention as embodied in the structures shown in the accompanying drawings, in which:

Figure 1 is a plan view of a float and mooring means in accordance with the invention.

Figure 2 is a side elevation of the structure shown in Figure 1, a derrick being additionally shown.

Figure 3 is an elevation like that of Figure 2, but with parts in a different relationship.

Figure 4 is an end elevation of the structure as shown in Figure 3.

Figure 5 is a section substantially on line 5—5 of Figure 1.

Figure 5a is a plan view of an anchor.

Figure 6 is a fragmentary view on an enlarged scale showing in elevation releasable guy anchoring means which appear also in Figures 2 and 3.

Figure 7 is a section substantially on line 7—7 of Figure 6.

Figure 8 is a fragmentary view on an enlarged scale showing in elevation a bracket which appears also in Figures 2, 3 and 5.

Figure 9 is a section substantially on line 9—9 of Figure 8.

Figure 10 is a fragmentary view on the scale of Figure 8 showing in vertical longitudinal section a releasable coupling which appears also in Figures 2 and 3.

Figure 11 is a section substantially on line 11—11 of Figure 10.

Figure 12 is a plan view of the structure of Figure 1 on a smaller scale and showing horizontal mooring means in operative disposition.

Figure 13 is a side elevation of the structure as shown in Figure 12.

Figure 14 is an end elevation of the float and anchorage means on the scale of Figures 12 and 13, but showing a different arrangement of horizontal mooring means, and

Figure 15 is a plan view of the arrangement shown in Figure 14.

Referring to the drawings, reference numeral 20 generally designates a flat rectangular platform or deck structure here shown as comprising three sections 21, 22 and 23 rigidly connected together. The platform structure comprises longitudinal truss members of which a side member is indicated at 24, Figure 2, and transverse truss members, of which an end member is indicated at 25, Figure 4. As shown in Figure 1, the center section 22 comprises longitudinal and transverse beams 26 and 27 defining a central symmetrically disposed square 28 which includes further transverse members 29. Provided at the center of the square is a circular opening 30 through which the well building operations can be carried out.

Reference numerals 31 and 32 designate opposed parallel channel members secured to the top of the platform in equally spaced relation from the longitudinal central plane of the platform, the channels receiving the wheels of a truck 33 on which is mounted a derrick 34 whose structure is open at the left, Figure 2. The lower end of the derrick is angled to a transverse pivot 35 supported on the truck 33 and rests against and is normally secured to triangular frame members 36 and 37 which are secured to the truck. Also mounted on the truck is a draw works 38 controlling cables 39 and 40, of which the former is led beneath a guide pulley 41 mounted on the derrick, and thence to a crown block 42 and a travelling block 43. Cable 40

runs to the top of the derrick, and when the derrick is unlocked from the frame members 36 and 37, it can swing to the left under the control of cable 40, and the travelling block can accordingly swing outwardly of the derrick as permitted by the open structure at the left. Thus, by running the truck 33 to the left-hand end of the rails Figure 2, the derrick can operate off of the left-hand end of the platform. In Figure 2 the truck is locked to the rails with the travelling block directly above the opening 30.

Secured beneath the deck structure 20 are, as here shown, eight columnar buoyancy units 44 to 51, which may all be of the construction particularly shown in Figure 5. The buoyancy units are equally spaced longitudinally of the platform, the transverse spacing is the same as the longitudinal spacing, as here shown, and the units are symmetrically disposed with respect to the platform.

Referring to Figure 5, the unit 47 comprises a vertical cylindrical member 52 which extends through to the top of the platform and is rigidly secured thereto. A vertical cylindrical member 53 surrounds member 52 concentrically therewith and has its upper end rigidly fixed to the bottom of the platform. Below member 53 a further cylindrical member 54 surrounds member 52 concentrically therewith, member 54 terminating downwardly in a conical formation 55 which extends into member 52 just above the lower extremity thereof and is sealed thereto. Member 53 is divided into a number of watertight compartments by horizontal annular partitions 56, and member 54 is separated into compartments by sealed partitions 57 and 58 providing compartments 59, 60 and 61, of which the latter is water-tight. Compartment 59 has bottom openings as at 62, and compartment 60 has bottom openings as at 63, these openings being just above the partitions 57 and 58, respectively. A pipe 64 extends from the top of compartment 59 to a valve 65, and thence to a source of compressed air 66, the valve and source being disposed in the deck structure. The top of compartment 60 is similarly connected by a pipe 67 with a valve 68 and source of compressed air 69. The valves 65 and 68 are of the four-way type, having a shut-off position, a position in which the pipes 64 and 67 are open to the atmosphere, and a position in which the pipes are connected to the compressed air sources. In the first position of the valves, with tanks 59 and 60 empty, the tanks will remain substantially so even though the compartments are submerged. With the compartments submerged, the valves in the second-mentioned position will permit flooding of the compartments to any desired extent, water entering freely through the openings 62 and 63. In the third position of the valves, compressed air can be introduced to one or both of the buoyancy compartments to blow them out in whole or in part. The various compartments are preferably reinforced by radial plates. When such plates are used in compartments 59 and 60, they are perforated or otherwise formed so that the pipes 64 and 67 will communicate with the respective compartments throughout.

Adjacent sides of the lower enlargements, as at 54, of the buoyancy units have fixed thereto brackets 70 of the form particularly shown in Figures 8 and 9, these brackets being secured to the enlargements at the same level, which is preferably that of the partitions as at 57. Each bracket 70 comprises parallel vertical flanges 71

and 72 pierced to receive bolts 73 and 74 and to receive a bolt 75 on which is rotatable a pulley 76. The bolts 74 of opposed brackets engage fittings, as at 78, in which are seized the ends 5 of diagonal guys as at 79, which run upwardly and are anchored to the bottom of the platform. This arrangement applies between all of the buoyancy units, except the units 47 and 49, where a special releasable bracing system is provided for 10 a purpose which will later appear.

Referring to Figures 2, 8 and 9, columns 47 and 49 are equipped with opposed brackets 70 and have pivoted to their bolts 74 strut parts 80 and 81 having normally interengaged hooked ends 82 and 83, as particularly shown in Figure 11. Reference numeral 84 designates a sleeve which holds the ends in interengaged relation. By moving the sleeve to the right against a compression return spring 85, the joint is uncovered and the parts 80 and 81 may be swung upwardly by pulling on cables 86 and 87, Figure 2, which run to the deck. The sleeve can be moved to uncoupling relation by pulling on a cable 88 which runs to the pulleys 76 of the adjacent fitting 70, and thence to the deck. The diagonal guys 89 and 90 extend from the brackets 70 to identical slides 91 and 92 which engage over the bottom flange portion 93 of truss 24. The slide 92, Figures 6 and 7, comprises side plates 94 and 95 bolted together through a spacer 96 which is engaged by a yoke 97 whose arms are received in openings in a head 98 fixed to the end of cable 90 and engaged by nuts 99 and 100. By pulling the slide 92 to the left, Figure 6, by means of a wire 101, cable 90 will be tautened, and the slide retained by means of a pivoted dog 102, which can be released by pulling on a control wire 103. The locking dog for slide 91 is indicated by the reference numeral 104, Figure 2.

Referring to Figure 1, the four buoyancy columns at the left are connected by diagonal horizontally disposed ties 105 and 106, and the four columns at the right are connected by similar ties 107 and 108. Such ties are omitted at the center section, and, instead, diagonally arranged trusses 109 to 112 are provided, these extending from the columns to the corners of the square structure 28 for the rigid support of the center section against the weight of the derrick and other equipment.

As here shown, weight anchors 113 to 120 are associated with the buoyancy units, these anchors being all of the construction particularly shown in Figures 5 and 5a. Referring to that figure, the anchor 116 comprises a frustoconical outer wall 117' and an inverted frustoconical top wall 118' providing a recess adapted to receive the lower conical end of the buoyancy column 47 with clearance for the projecting extremity of member 52. Spacer strips 119' are secured to the top wall 118' in radial planes. A frusto-conical wall 120' is secured to the lower edge of top wall 118', and its lower edge is connected with the outer shell 117' through an annular wall 121', 65 so that a buoyancy tank or compartment 122 is provided. Wall 120' has secured thereto a reinforced bottom wall 123, to which is centrally fixed an upright member 124 bifurcated at its upper end and supporting a transverse pin 125. Wall 120' and bottom plate 123 define a compartment which may contain ballast 126 in the form of scrap iron, concrete, or the like. The lower edge of the outer wall 117' is interiorly rimmed by a relatively narrow annulus 127, the connection being reinforced by gussets 128. Below wall 121

the wall 117' is provided with radial slots 128 which provide communication between the outside of the shell and the downwardly open annular space 130.

Mounted in the upper end of member 52 is a crown block 131 from which is suspended a travelling block 132 by means of a hoisting cable 133, the travelling block having a hook 134 engaged with the pin 125. The upper end of cable 133 is led to a winch 135 mounted in the platform structure and effective to pay out or take in the cable and to retain or lock the cable in any adjusted relation.

Reference numeral 136 designates a flexible hose connected at its lower end to a pipe 137 whose open end is disposed at the top of compartment 122, the latter being provided with bottom openings 138 in wall 120'. The hose is led up through the passage or shaft defined by member 52 and over a pulley 139 to a drum 140 provided with a suitable drive for winding, unwinding, and locking. The drum end of the hose is in connection through a swivel coupling with a pipe 141 which leads through a valve 142 to a source of compressed air 143. Valve 142 is a four-way valve, the same as valves 65 and 68.

Reference numeral 144 designates a guy connected to the upright 124 of anchor 116 and running across to the pulley 16 of the bracket 70 on the adjacent side of column 48, and thence upwardly to a winch 145 mounted in the platform. The spacer strips 119 provide clearance for the guy 144 so that the anchor 116 can be pulled into contact with the bottom of the column without cocking. A similar guy 146 runs to the bracket 70 on column 47, and thence to a winch 147. Similar diagonal guys are provided between all of the buoyancy columns and anchors, except columns 47 and 49 and associated anchors. In Figure 4 the end diagonal guys are designated 144' and 146'.

In Figure 2 the anchors are all shown as being held against the bottoms of the columns and all ballast compartments are assumed to be empty. In such case the structure is in condition to travel to the point of use with the least possible draft, and the water line in this case will be at X with a draft of, say, 20 feet. The total height of the float and anchors in the relation shown in Figure 2 is 95 feet in the present example, and with this figure as a base, the other proportions will be evident.

Assuming that the water at the location to be drilled is not over about 65 feet deep, when the structure is in position the buoyancy tanks of the anchors and the lower buoyancy unit compartments or tanks can be filled with water, with the result that the anchors will be bottomed in supporting relation to the float. The relation of parts will remain the same as shown in Figure 2, but the water line may be, for example, at Y. Under the circumstances just mentioned, the anchors might be carried by the buoyancy columns by being integrally joined thereto.

A float proportioned as in the present example will have a total weight of from 1200 to 1400 tons with a buoyancy of 3000 tons, giving a maximum residual buoyancy of from 1600 to 1800 tons. The capacity of the ballast tanks of the buoyancy units is such that when the tanks are filled with water, the total buoyancy effect will be over-balanced. Each anchor has a weight of 250 tons, submerged, and, consequently, there is a total anchoring weight of 2000 tons which is considerably enhanced by the clinging effect which devel-

ops after the anchors are bottomed. Therefore, with all buoyancy tanks fully flooded and the anchor cables 133 tensioned, the float is firmly seated in a manner not to be influenced by water disturbances.

In the situation just discussed, the float rests on the anchors with the weight which is in excess of the total buoyancy effect of the buoyancy units. However, the ballast tanks of the buoyancy units 10 may be blown out to restore the residual buoyancy in whole or in part, and, in that case, the anchors alone will serve as the hold down means. When it is desired to move the float, it is only necessary to blow out the anchors through the openings 138 which, it will be noted, are directed beneath the bottom plate 123. The issuing water serves to break the clinging effect. When the anchor tanks are fully blown out, each anchor, as contemplated in the present example, has a buoyancy effect of 50 tons which supplements the buoyancy effect of the buoyancy units.

It will be evident that with the described relationship, it would be impossible for the float to lift the full weight of the anchors, which is 2000 tons as against the 1600 to 1800 tons maximum residual buoyancy of the float. However, by blowing out the tanks to a suitable extent they can be readily lifted, and by blowing them out completely they add a considerable buoyancy effect of their own, as above-mentioned.

Where the water is deeper, as contemplated in Figures 3 and 4, when the location is reached the anchors may be flooded and lowered to the bottom, and then the winches operated to pull the float down so that the bottom of the platform is, say, 30 feet above the water level. Since the anchor tackles are individually operable the platform can be pulled to an exactly level service draft or condition, regardless of bottom irregularities. With the ballast tanks of the buoyancy units empty, there may be an upward pull as high as 250 tons per anchor and such a tension effect will maintain the float against any rolling and pitching, regardless of wave conditions. As the anchors are lowered the guys as at 144 and 146 are also paid out and then tautened so that the buoyancy units are maintained directly above their associated anchor units. In Figures 3 and 4 the depth is assumed to be 165 feet and up to this depth the guys have a good stabilizing effect. When greatly below this depth it is preferable to use the horizontal mooring cables whose arrangement will be later described.

In reaching a setting such as is shown in Figures 3 and 4 it is more economical to flood the ballast tanks of the buoyancy units along with the ballast tanks of the anchors, decreasing the residual buoyancy until the float is lowered to the desired depth, for example, with the platform 30 feet above water, as above mentioned. When the anchors have bottomed and the anchor cables have been locked, the buoyancy unit ballast tanks may be blown out in order to tension the anchor cables. This manner of procedure is much more economical than that first mentioned, since it obviates the necessity for the very powerful winches which are required to haul the float down with its ballast tanks empty.

As another possibility, the same residual float buoyancy of 1600 to 1800 tons may be assumed, but assume that the anchors are partly blown out so that each has an effective submerged weight of 125 tons for an aggregate of 1000 tons. Under these circumstances the anchors would obviously not suffice, at least by weight alone, to

hold the buoyancy units submerged below their normal flotation level. However, under the assumed circumstances, the buoyancy units can be flooded so that the residual buoyancy is, for example, 600 tons, and, in that case, the total anchor weight of 1000 tons will suffice for hauling down. By blowing the float ballast tanks and resuming total residual buoyancy, the anchors can be lifted without being blown at all, and in this case it would be the same as though anchors of fixed effects were used.

In Figures 12 and 13 the float is shown as anchored in 300 feet of water and positioned by means of horizontal mooring cables 148 to 151 which extend from winches at the corners of the float (see Figure 2) down to sheaves at the top of the corner column enlargements and thence to anchors about 1200 feet away from the float, the cables lying in planes which substantially bisect the corner angles of the float, as here shown. In Figure 3 a well casing 152 is shown as projecting above the water to within a short distance of the platform. Assuming the well to have been completed and that the float is to be moved, the anchors are hauled up and the structure will rise but strut portions 80 and 81, at least, will still be below the top of the casing. The strut portions are disconnected and swung upwardly and, if necessary, slides 91 and 92 are released and pulled together so that guys 89 and 90 are slackened and can be picked up by a hook and lifted above the height of the casing. Then by manipulating the horizontal mooring cables the float can be moved laterally away from the casing which is cleared by reason of the release of the strut members 80 and 81 and the cables 89 and 90, these being thereupon returned to operative relation. The horizontal cables may then be used to move the rig to a new location, the anchors being re-set as required.

In Figures 14 and 15 a more complete horizontal mooring system is shown in that eight cables 160 to 167 are provided, two extending from each corner at right angles to an end and side of the float respectively. The disposition is shown for depths of one hundred, two hundred, and three hundred feet. At the one hundred foot depth the cables are anchored three hundred feet away from the float and six hundred feet away at the two hundred foot depth. At these depths the cables can be supplemented by the guys as at 144' and 145' or the cables alone or the guys alone may be used. At the three hundred feet depth the cables are shown as anchored a thousand feet away from the float and the guys are omitted since at this depth they would be too steep for an adequate effect. Where the mooring cables are of such length that their weight would cause them to sag substantially I provide them with readily attachable and detachable buoys 168 so that they are maintained substantially straight, as shown. Each cable runs to a separate winch on the float and the buoys are attached as the cables are paid out and removed as the cables are taken in.

While I have shown an anchor associated with each buoyancy unit it should be understood that this need not necessarily be always the case. When the following claims mention submerging the buoyancy units below their normal flotation level, the level referred to is that established by the residual buoyancy of the float as determined by the condition of the float ballast tanks. I do not limit myself to the form and arrangement of

parts herein specifically disclosed except as in the claims.

I claim:

1. In combination, a float comprising a platform structure, vertical columnar buoyancy units beneath said platform structure for the support of the same, weight anchors beneath said platform structure, vertically extending cables in connection with said anchors respectively, winches carried by said platform structure in connection with said cables for the independent control thereof including the locking thereof in any adjusted relation, each of said anchors including a buoyancy tank, and means for controllably flooding and emptying said tanks whereby said anchors can be adjusted so that when bottomed they are capable of holding said buoyancy units submerged below the normal flotation level thereof or so that they are liftable by the buoyancy effect of said buoyancy units to permit movement of the float to another location, the height of the buoyancy units and the horizontal distribution of the buoyancy units and anchors being such and the hold-down capacity of the anchors being such as to enable the buoyancy units to be held so far below their normal flotation level and with such tension on the cables as to render the anchored float maintainable against rolling and pitching regardless of wave conditions with the bottom of the platform above the tops of the waves.

2. In combination, a float comprising a platform structure, hollow vertical columnar buoyancy units beneath said platform structure for the support of the same, weight anchors beneath said platform structure, vertically extending cables in connection with said anchors respectively, winches carried by said platform structure in connection with said cables for the independent control thereof including the locking thereof in any adjusted relation, and means for controllably flooding and emptying said buoyancy units, said anchors being capable when bottomed and said buoyancy units suitably flooded of holding said buoyancy units submerged below their normal flotation level and being liftable by said buoyancy units when the latter are suitably emptied to permit movement of the float to another location, the height of the buoyancy units and the horizontal distribution of the buoyancy units and anchors being such and the hold-down capacity of the anchors being such as to enable the buoyancy units to be held so far below their normal flotation level and with such tension on the cables as to render the anchored float maintainable against rolling and pitching regardless of wave conditions with the bottom of the platform above the tops of the waves.

3. In combination, a float comprising a platform structure, hollow vertical columnar buoyancy units beneath said platform structure for the support of the same, means for controllably flooding and emptying said buoyancy units for the control of their buoyancy effect, weight anchors beneath said platform structure, vertically extending cables in connection with said anchors respectively, winches carried by said platform structure in connection with said cables for the independent control thereof including the locking thereof in any adjusted relation, each of said anchors including a buoyancy tank, and means for controllably flooding and emptying said tanks, said anchors being capable when bottomed and they and the buoyancy units suitably flooded of holding said buoyancy units submerged below

their normal flotation level, and when they and the buoyancy units are suitably emptied being liftable by said buoyancy units to permit movement of the float to another location, the height of the buoyancy units and the horizontal distribution of the buoyancy units and anchors being such and the hold-down capacity of the anchors being such as to enable the buoyancy units to be held so far below their normal flotation level and with such tension on the cables as to render the anchored float maintainable against rolling and pitching regardless of wave conditions with the bottom of the platform above the tops of the waves.

4. In combination, a float comprising a platform structure, vertical columnar buoyancy units beneath said platform structure for the support of the same, each of said buoyancy units having a vertical passage therethrough, weight anchors beneath said buoyancy units respectively, cables in connection with said anchors and disposed in said passages, winches carried by said platform structure in connection with said cables for the independent control thereof including the locking thereof in any adjusted relation, each of said anchors including a buoyancy tank, and means for controllably flooding and emptying said tanks, said anchors being capable when bottomed and their tanks suitably flooded of holding said buoyancy units submerged below their normal flotation level and when their tanks are suitably emptied being liftable by said buoyancy units to permit movement of the float to another location, the height of the buoyancy units and the horizontal distribution of the buoyancy units and anchors being such and the hold-down capacity of the anchors being such as to enable the buoyancy units to be held so far below their normal flotation level and with such tension on the cables as to render the anchored float maintainable against rolling and pitching regardless of wave conditions with the bottom of the platform above the tops of the waves.

5. In combination, a float comprising a platform structure, hollow columnar buoyancy units beneath said platform structure for the support of the same, means for controllably flooding and emptying said buoyancy units for the control of their buoyancy effect, each of said buoyancy units having a vertical passage therethrough, weight anchors beneath said buoyancy units respectively, cables in connection with said anchors and disposed in said passages, winches carried by said platform structure in connection with said cables for the independent control thereof including the locking thereof in any adjusted relation, said anchors being capable when bottomed and said buoyancy units suitably flooded of holding said buoyancy units submerged below their normal flotation level and being liftable by said buoyancy units when the latter are suitably emptied to permit movement of the float to another location, the height of the buoyancy units

and the horizontal distribution of the buoyancy units and anchors being such and the hold-down capacity of the anchors being such as to enable the buoyancy units to be held so far below their normal flotation level and with such tension on the cables as to render the anchored float maintainable against rolling and pitching regardless of wave conditions with the bottom of the platform above the tops of the waves.

10 6. In combination, a float comprising a platform structure, vertical columnar buoyancy units beneath said platform structure for the support of the same, means for controllably flooding and emptying said buoyancy units for the control of their buoyancy effect, each of said buoyancy units having a vertical passage therethrough, weight anchors beneath said buoyancy units respectively, cables in connection with said anchors and disposed in said passages, winches carried by said platform structure in connection with said cables for the independent control thereof including the locking thereof in any adjusted relation, each of said anchors including a buoyancy tank, and means for controllably flooding and emptying said tanks, said anchors being capable when bottomed and they and the buoyancy units suitably flooded of holding said buoyancy units submerged below their normal flotation level, and when they and they buoyancy units are suitably emptied being liftable by said buoyancy units to permit movement of the float to another location, the height of the buoyancy units and the horizontal distribution of the buoyancy units and anchors being such and the hold-down capacity of the anchors being such as to enable the buoyancy units to be held so far below their normal flotation level and with such tension on the cables as to render the anchored float maintainable against rolling and pitching regardless of wave conditions with the bottom of the platform above the tops of the waves.

15 7. A float of the type described comprising a deck, a supporting structure therefor, a plurality of buoyancy units secured in spaced relation in and forming a part of the supporting structure, said buoyancy units in the aggregate giving the float substantial residual buoyancy when riding at service draft, some at least of said buoyancy units having a central shaft open at the bottom, and hoisting means in said shafts adapted to be connected to anchorage means.

20 8. A float of the type described comprising a deck, a supporting structure therefor, a plurality of buoyancy units secured in spaced relation in and forming a part of the supporting structure, said buoyancy units in the aggregate giving the float substantial residual buoyancy when riding at service draft, some at least of said buoyancy units having a central shaft open at the bottom, and block and tackle hoisting means in said shafts adapted to be connected to anchorage means.

EDWARD R. ARMSTRONG.
